(57) **CLAIM**

The ornamental design for a heel-toe shifter assembly for a three-wheeled vehicle, as shown and described.

DESCRIPTION

FIG. 1 is an isometric view of a heel-toe shifter assembly for a three-wheeled vehicle of the present invention.

FIG. 2 is a front view of the heel-toe shifter assembly for a three-wheeled vehicle.

FIG. 3 is a right view of the heel-toe shifter assembly for a three-wheeled vehicle.

FIG. 4 is a rear view of the heel-toe assembly for a three-wheeled vehicle.

FIG. 5 is a left side view of the heel-toe assembly for a three-wheeled vehicle.

FIG. 6 is a top view of the heel-toe assembly for a three-wheeled vehicle.

FIG. 7 is a bottom view of the heel-toe assembly for a three-wheeled vehicle; and,

FIG. 8 is the isometric view shown in FIG. 1 of a heel-toe shifter assembly for a three-wheeled vehicle with broken line representations for a pair of unclaimed pedal structures.

The broken lines shown in the drawings illustrate portions of the heel-toe shifter assembly for a three-wheeled vehicle that forms no part of claimed design.
